CHECKWRITER

Samuel J. Boker, Brooklyn, Gerald S. Lazarus, Bethpage,
and Judah R. Sassoon, Jackson Heights, N. Y.

Application February 20, 1958, Serial No. 49,718

Term of patent 14 years

(Cl. D64—11)

Fig. 1 is a top view of a checkwriter showing our new design;

Fig. 2 is a rear view with part of the operable handle being deleted for convenience of illustration;

Fig. 3 is a right side view with part of the handle arms being shown broken away; and

Fig. 4 is a left side view thereof with parts of the handle arms being shown broken away.

We claim:

The ornamental design for a checkwriter, as shown.
